his Attorney

UNITED STATES PATENT OFFICE.

JOHN M. SANDERS, OF ATLANTA, GEORGIA.

PEA-HULLER.

1,295,605.

Specification of Letters Patent. Patented Feb. 25, 1919.

Original application filed February 9, 1916, Serial No. 77,183. Divided and this application filed April 17, 1918. Serial No. 228,990.

To all whom it may concern:

Be it known that I, JOHN M. SANDERS, a citizen of the United States, residing at Atlanta, in the county of Fulton and State 5 of Georgia, have invented certain new and useful Improvements in Pea-Hullers, of which the following is a specification.

My invention relates to hullers for peas, beans and the like, and it consists in the 10 combinations, constructions and arrangements herein described and claimed.

The present application is a division of my prior application Serial No. 77,183, filed February 9, 1916. In the prior application 15 aforesaid, the claims were drawn to a huller having means for separating the hulls from the peas or beans in which pneumatic means were made use of in this separation and in which means were provided for preventing 20 the ejection of the peas or beans with the hulls.

The main feature of the present application lies in the provision of a perforated plate for separating the peas or beans from 25 the chaff which remain from the initial separation by the pneumatic means aforesaid, and in the provision of a device for keeping the perforated plate from clogging up.

30 A further object of the present invention is to provide a pea or bean huller having a perforated plate which is raked constantly from end to end in one direction by means of rakes or drags having teeth spaced apart 35 so as to permit the peas or beans to be passed by the teeth while the chaff is carried along by the teeth and eventually ejected by the machine.

In the present application I have disclosed substantially the same apparatus as 40 that disclosed in the prior application aforesaid, since such disclosure is necessary for a clear understanding of the mechanism which forms the novel feature of the present invention.

45 My invention is illustrated in the accompanying drawings which form part of this application and in which:

Figure 1 is a side elevation of one side 50 of the machine.

Fig. 2 is a vertical longitudinal section through the device.

In carrying out my invention, I provide 55 a casing 1 which may be of any suitable form and material.

In the upper portion of the said casing a hopper 2 is provided, the said hopper being connected by a throat 3 with the interior of a toothed concave 4, in which is disposed a toothed cylinder 5. The teeth of the concave and cylinder are spaced in such manner as to shell the peas or beans without splitting, cracking or otherwise injuring the same.

From the lower portion of the concave 4 the 60 peas or beans and their hulls pass through a depending conduit 6 to the bottom of a discharge spout 7 for hulls; the said spout being carried through the rear end of the casing and being provided at its rear end with an upwardly extending transverse flange or other abutment 8, and being also provided beyond the casing with an upper wall 9 that terminates in a depending transverse flange or other abutment 10. The spout 7 is for the 65 discharge of the bulk or major portion of the hulls under the action of a blast of air from a rotary fan 11, and the abutment or flange 8 serves to prevent any peas or beans that may be moved up the spout 7 from 70 being driven out of the machine. Manifestly the hulls and chaff will be blown over the flange 8 but the peas or beans will bring up against and be turned back by the flange, and will then gravitate through 75 the spout to the lower end of the bottom thereof. The upper abutment or flange 10 serves to arrest and turn back any peas or beans that may ride upwardly on the hulls, and this without interfering with the free 80 escape of the hulls and chaff between the two flanges 8 and 10.

The fan 11 is disposed in a casing 12, and from said casing a trunk 13 extends rearwardly to a point in front of the throat 6 85 and above the lower forward end of the bottom of the spout 7.

From the lower forward end of the bottom of spout 7, the peas or beans and portions of the hulls, chaff and other refuse, 100 pass by gravity through an opening 14 and in rear of a curvilinear wall 15 and are deposited on a foraminous plate 16. This plate is capable of being withdrawn from the casing; the scheme being to use one 105 plate when peas, particularly cow peas, are to be hulled, and a plate having larger apertures when beans such as velvet beans are to be shelled. The peas or beans, as the case may be, drop through the apertures of 110

the plate 16 in company with a portion of the hulls and chaff, and fall upon an imperforate inclined support 17 by which the peas or beans alone are conducted to a box 5 or other receptacle, placed at the point indicated by 18 in Fig. 2. A discharge opening 18^a for hulls and other refuse is provided between the rear ends of the plate 16 and support 17, and a casing 19 containing a rotary fan 20 is connected through a trunk 21 with the forward end of the space between the plate 16 and support 17, this in order to assure all of the small portions of the hulls, chaff and other refuse 10 being separated from the peas or beans 15 precedent to the delivery of the latter to the box 18.

It is important that the apertures of the plate 16 be kept clear during the operation 20 of the machine so as to enable the peas or beans to pass through said apertures to the support 17. I therefore provide above the plate 16 an endless drag 22. The said drag 22 comprises sprocket or other suitable belts 23 and spaced transverse bars 24 on which are steel teeth or spikes 25. The lower stretch of the drag is opposed to and parallel with the upper side of the foraminous plate 16, and the teeth or spikes 25 are disposed 25 at approximate right angles to the plate, and hence in its rearward traverse the lower stretch of the drag will operate to carry such hulls, chaff and other refuse as find their way to the plate 16 out of the 30 machine, thereby maintaining the plate 16 in a clear state for the passage of peas or beans, obviating choking or clogging of the machine, and materially promoting the efficiency of the machine as a whole.

40 It will be observed that the drag 22 traverses the entire length of the perforated plate 16 from the lower to the upper end in a direction parallel to the plate. This

is a prime importance because it is only by this means that the perforations in the plate 45 16 may be kept clear.

Having described my invention, what I claim and desire to secure by Letters Patent, is:

In a huller, a casing having an opening 50 formed in one end thereof, a removable foraminous plate arranged within the casing and inclined and extending upwardly toward and through said opening, an endless drag arranged within the casing near 55 and above the foraminous plate and having a lower turn arranged parallel with the foraminous plate and extending throughout the entire length of said foraminous plate, teeth carried by the endless drag and disposed at substantially a right angle with relation thereto and adapted to remove material from the openings in the foraminous plate and to propel material longitudinally of said foraminous plate, a curved plate 60 arranged at the lower end of the foraminous plate to conduct beans and hulls to the lower end of the foraminous plate and beneath the endless drag, an imperforate plate 65 arranged near and beneath the foraminous plate and inclined in the same direction and provided at its opposite ends with outlet openings, and a blower having an outlet 70 trunk arranged to supply air into the space between the imperforate plate and the foraminous plate, at a point above the outlet opening at the lower end of the imperforate plate, the outlet trunk having its upper side 75 wall arranged flush with and in end-to-end relation to the foraminous plate.

In testimony whereof I affix my signature in presence of two witnesses,

JOHN M. SANDERS.

Witnesses:

A. H. McDONALD,
W. A. MEDLOCK.
